US00D583244S

(12) **United States Design Patent**
Weyland et al.

(10) **Patent No.:** **US D583,244 S**
(45) **Date of Patent:** **** Dec. 23, 2008**

(54) **CONTAINER**

(75) Inventors: **Guillermo Weyland**, Santiago (CL);
Robert Monaghan, London (GB);
Fernando Muniz-Simas Moreira,
Santiago (CL); **Pepijn Rutger van der Krog**, Santiago (CL); **William H. Lunderman**, New York, NY (US);
Bruce Cummings, New York, NY (US)

D315,672 S 3/1991 Peykoff
5,069,612 A 12/1991 Teutsch et al.
5,110,521 A 5/1992 Moller
5,116,547 A 5/1992 Tsukahara et al.

FOREIGN PATENT DOCUMENTS

(73) Assignee: **Colgate-Palmolive Company**, New York, NY (US)

EP 1547751 6/2005

(**) Term: **14 Years**

(Continued)

(21) Appl. No.: **29/281,604**

(22) Filed: **Jun. 27, 2007**

(51) LOC (8) Cl. **09-03**

(52) U.S. Cl. **D9/531**

(58) Field of Classification Search D9/516,
D9/523, 528, 530, 531, 535, 565, 567, 575;
215/40, 44, 45, 200, 243, 329, 379-386,
215/395, 396, 398, 399

See application file for complete search history.

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of threads, part of the top portion and part of the bottom portion of the container is for illustrative purposes only and forms no part of the claimed design.

1 Claim, 6 Drawing Sheets
